EAR PROTECTOR

Harry Zaretsky, Brooklyn, N. Y.

Application June 7, 1935, Serial No. 25,399

6 Claims. (Cl. 132—45)

This invention relates to new and useful improvements in an ear protector.

The invention has for an object the construction of an ear protector which is very inexpensive and which is adapted to be very easily engaged on the ears to protect the ears during a hair or scalp treatment.

More particularly, the invention contemplates the construction of an ear protector which is characterized by a sheet of material of substantially oval shape to cover the ear, and which has a crease along the major axis, and upon one end of which there is a strip of material of a different width than the adjacent area of the oval shaped material, attached in edge alignment therewith so as to form a pocket between the strip and the sheet into which the top edge of one's ear may be engaged.

Still further the invention proposes the arrangement at the lower portion of said crease of an open area at which the adjacent material portions overlap and are attached together so to extend the pocket across the entire area of the sheet material.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is an elevational view of the inner side of an ear protector constructed according to this invention.

Fig. 2 is an edge view of Fig. 1.

Fig. 3 is a developed view of the material used in constructing the ear protector.

Fig. 4 is a sectional view taken on the line 4—4 of Fig. 1.

Fig. 5 is a developed view of an ear protector constructed according to another embodiment of the invention.

Fig. 6 is an elevational view of the inner side of an ear protector made from the blank shown in Fig. 5.

Fig. 7 is an edge elevational view of Fig. 6.

Fig. 8 is a developed view of the blank of an ear protector according to another embodiment of the invention.

Fig. 9 is an elevational view looking from the

inner side of the ear protector made from the blank shown in Fig. 8.

Fig. 10 is a fragmentary enlarged sectional view taken on the line 10—10 of Fig. 9.

The ear protector, according to this invention, includes a sheet of material 10, paper or other similar flexible material of substantially oval shape and formed with a crease 11 along its major axis. A strip of material 12 is arranged on one of the ends of the oval shape and is of a different normal width than the adjacent area of the oval shape and is attached in edge alignment with said area so as to form a pocket 13 between the strip and the sheet and into which the top edge of one's ear may be engaged. The lower portion of the crease 11, within the boundary divided off by the line A, is open and the material portions on the adjacent sides of the opening are overlapped and attached together so as to extend the pocket 13 completely across the entire area of the sheet material. Thus, the ear protector is adapted to cup the ear when engaged in position.

The strip 12 should be integral with the sheet of material 10 if a low cost ear protector is desired. In Fig. 3 a developed view of the ear protector is shown to illustrate this construction. The strip 12 is connected with the sheet 10 by a connecting portion 14. The natural width of the strip 12 is slightly greater than the natural width of the sheet 10, as may be seen in Fig. 3, especially by the dot and dash lines 12' which indicate the strip 12 bent downwards over the top portion of the sheet 10. The side edges of the strip 12 and the sheet 10 are forced into edge alignment with each other, which is possible because of the crease 11 which merely bows outwards, and the aligned edges are secured together by staples 15. The overlapping areas of the material 10 at the lower portion of the crease 11 are secured together by a staple 16, or the like.

The ear protector is used by merely placing it over the ear so that the sheet 10 extends across the ear and the strip 12 engages over the top portion of the ear to support the protector. The protector will readily maintain its position, as usually some of the hair or apparatus is engaged over the ears during the treatment.

In Figs. 5—7 inclusive another embodiment of the invention has been disclosed which distinguishes from the prior form merely in the construction of the supporting strip. More particularly, this ear protector has a strip 12^a which normally is of a smaller width than the normal width of the sheet 10, as may be clearly seen by

the dot and dash lines 12^{aa} which represent the strip 12 bent downwards. Furthermore, the shape of the strip 12 distinguishes from the shape of the corresponding prior strip in that it has a bottom straight edge, contrasted with a concaved edge in the previous form.

The protector has the edges of the strip 12^a and the material 10 in edge alignment with each other and attached together by the staples 15. The 10 pocket will be formed in a similar fashion as the pocket 13 previously described. In other respects this form of the invention is identical to the previous form and corresponding parts may be recognized by the same reference numerals.

15 In Figs. 8-10 inclusive, a still further modified form of the invention has been disclosed in which the ear protector comprises a sheet of material 10^b substantially of oval shape and formed with a crease 11^b along its major axis. At the top, the oval sheet 10^b is formed with a lip portion 12^c which is bent into the form of a hook adapted to engage over the top of the ear. The lower portion of the crease 11^b, indicated by the area A, is cut open and the materials overlapped and held together by the staple 16.

20 In this form of the invention the pocket is not as pronounced as in the previous form, and therefore not as satisfactory, but this form of the invention has the advantage of lower cost of manufacture.

25 While I have illustrated and described the preferred embodiment of my invention, it is to be understood that I do not limit myself to the precise construction herein disclosed and the right is reserved to all changes and modifications coming within the scope of the invention as defined in the appended claims.

30 Having thus described my invention, what I claim as new, and desire to secure by United States Letters Patent is:—

35 1. An ear protector, comprising a sheet of material of substantially oval shape and creased along the major axis, a strip on one of the ends of said oval shape and of a different width than the adjacent area of the oval shape and attached in edge alignment with said area so as to form a pocket between said strip and sheet into which the top edge of one's ear may be engaged, and the lower portion of said crease being open with 40 the adjacent material portions overlapping and attached together for extending said pocket across the entire area of said sheet of material.

45 2. An ear protector, comprising a sheet of material of substantially oval shape and creased along the major axis, a strip on one of the ends of said oval shape and of a different width than the adjacent area of the oval shape and attached in edge alignment with said area so as to form a pocket between said strip and sheet into which the top edge of one's ear may be engaged, and 50 the top edge of one's ear may be engaged, and

the lower portion of said crease being open with the adjacent material portions overlapping and attached together for extending said pocket across the entire area of said sheet of material, said strip having a small area thereof connecting with and integral with said sheet of material. 5

3. An ear protector, comprising a sheet of material of substantially oval shape and creased along the major axis, a strip on one of the ends of said oval shape and of a different width than the adjacent area of the oval shape and attached in edge alignment with said area so as to form a pocket between said strip and sheet into which the top edge of one's ear may be engaged, and the lower portion of said crease being open with the adjacent material portions overlapping and attached together for extending said pocket across the entire area of said sheet of material, staples engaging through the edges of the strip and the sheet for accomplishing the attachment 10 of these parts. 15

4. An ear protector, comprising a sheet of material of substantially oval shape and creased along the major axis, a strip on one of the ends of said oval shape and of a different width than the adjacent area of the oval shape and attached in edge alignment with said area so as to form a pocket between said strip and sheet into which the top edge of one's ear may be engaged, and the lower portion of said crease being open with the adjacent material portions overlapping and attached together for extending said pocket across the entire area of said sheet of material, 20 said strip being of a normal greater width than said sheet. 30

5. An ear protector, comprising a sheet of material of substantially oval shape and creased along the major axis, a strip on one of the ends of said oval shape and of a different width than the adjacent area of the oval shape and attached in edge alignment with said area so as to form a pocket between said strip and sheet into which the top edge of one's ear may be engaged, and the lower portion of said crease being open with the adjacent material portions overlapping and attached together for extending said pocket across the entire area of said sheet of material, 35 said strip being of a normal greater width than said sheet. 40

6. A new article of manufacture, comprising a single blank foldable to provide two sections outer and inner respectively, of an ear protector, portions of the outer section being movable to overlapping relation whereby to concave the outer section, the inner section being centrally cut-out 50 whereby to provide a substantially horseshoe-shape flanged rim extending to the horizontal medial line of the outer section. 55
